UNITED STATES PATENT OFFICE.

SAMUEL H. SCHENCK, OF ZIONSVILLE, INDIANA.

COMBINED CAMP-STOOL AND COT.

SPECIFICATION forming part of Letters Patent No. 571,579, dated November 17, 1896.

Application filed March 16, 1896. Serial No. 583,312. (No model.)

To all whom it may concern:

Be it known that I, SAMUEL H. SCHENCK, a citizen of the United States, residing at Zionsville, in the county of Boone and State of Indiana, have invented certain new and useful Improvements in a Combined Camp - Stool and Cot; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to a novel arrangement of well-known appliances by which a cot-bed may be converted into a number of camp-stools, and vice versa; and it consists of a peculiar arrangement of separable hinges, 20 in combination with camp-stools by which the stools are connected to form a cot-bed separated, or the whole folded into a small compass when connected as a cot, as will be more fully described hereinafter, and particularly 25 pointed out in the claims.

My object is to provide a folding cot which may be readily converted into a number of camp-stools, and, when desired, reconverted into a cot, and closely folded when desired 30 for storage or shipping, and with this object in view my invention fulfills the need of such an article, is furthermore easily and cheaply manufactured, of few parts, and durable in use.

35 Referring to the drawings, Figure 1 is a side elevation of stool-frames connected as a cot. Fig. 2 is a top plan of cot. Fig. 3 is an end elevation of one of the camp-stools or section of the cot detached, and Fig. 4 is a side view 40 of cot without cover when folded.

In the drawings, A, B, C, D, and E represent the detachable sections of the cot, each section being a complete camp-stool when separated from the others and having their 45 respective covers a, b, c, d, and e. The X-legs h and i of the stools are made, preferably, of wood, as well as the end legs f and g, which latter differ from the others principally in

being made somewhat longer at the upper ends to form an elevation for a head-rest. 50 Each stool or section has a pair of top rails R to which the cover is secured, and below the center are tie-braces k and l, which, when the legs are folded, lie in notches k' and l' in the opposite legs. Each pair of X-legs are 55 secured together near their centers by means of the pivotal rivets u, which are upset flush at outside of legs i i. In setting up and connecting the X-legs the leg i is set outside of the leg h, and in each stool these are crossed 60 in alternating directions, so that when the stools are placed together to form a cot the legs i of adjoining sections A and B are parallel, while the legs i of adjoining sections B and C, although parallel, lean in the opposite 65 direction or at a reverse angle. This alternation is necessary in order that when the cot is to be folded the sections lap backward and forward against each other. Each leg i is provided with two or more eyes m, protruding beyond the edge of the leg, so that when the legs i of two stools are placed against each other the eyes of the two stools are adjacent 70 and register with each other, permitting the insertion through them of the rod or hinge-pin n. When the cot is in use as such, these 75 hinges securely hold together all the sections, and simply withdrawing the rods separates the sections, when they become convenient camp-stools.

80 The tops or covers a, b, &c., may be made of any suitable material and may be secured to the rails in any suitable manner, but for a cheap and portable combination canvas is usually used, while the whole may be made 85 on a more elaborate scale throughout when desirable.

The various views so fully illustrate my invention that further description is not deemed necessary.

Having described my invention, what I claim, and desire to secure by Letters Patent, is—

90 1. The herein-described cot comprising a number of folding camp-stools provided with 95 loose pin-hinges situated alternately at each

side of the cot, whereby the stools or sections of the cot are connected and enabling them to be folded in a serpentine manner, substantially as and for the purposes shown and described.

2. The combination of the series of stools to make a cot, the adjoining X-legs of which are alternately provided with aligned eyes, and the rods or pintles completing the hinge;

whereby said stools may be folded or collapsed, or separated from each other, substantially as shown and described.

In testimony whereof I affix my signature in presence of two witnesses.

SAMUEL H. SCHENCK.
